(57) CLAIM

The ornamental design for a household grater, as shown and described.

DESCRIPTION

FIG. 1 is a top, rear and left side perspective view of the household grater comprising a grater and a cover positioned under the grating surface;

FIG. 2 is a bottom, rear and right side perspective view thereof;

FIG. 3 is a top view thereof;

FIG. 4 is a bottom view thereof;

FIG. 5 is a left side view thereof;

FIG. 6 is a right side view thereof;

FIG. 7 is a rear view thereof; and,

FIG. 8 is a front view thereof.

The broken lines shown in the drawing views are included for illustrative purposes only and are not intended to limit the claimed design.
